UNITED STATES PATENT OFFICE.

JAMES W. PHELPS, OF CHICAGO, ILLINOIS.

ELECTRIC RECEPTACLE.

Application filed May 24, 1924. Serial No. 715,555.

My invention relates to improvements in receptacles for incandescent electric lamps which are provided with thermoelectric means for causing the electric lamps to 5 flash.

The object of my invention is to provide a receptacle of this kind which shall be exceedingly simple in construction and assembly, which shall be readily adjustable as 10 to periodicity of flashing, and in which the thermo element shall be amply protected, while at the same time being sufficiently exposed for rapid operation.

A particular feature of my invention relates to a porcelain socket member provided 15 with protecting walls rising along side of the socket and providing a protected space for the thermo element, and whereby a relatively long element can be made use of 20 without unduly enlarging the porcelain base.

For a clear understanding of my invention reference is had to the accompanying drawings forming part of this specification 25 in which:—

Figure 1, is a side elevation of a receptacle made in accordance with my invention;

Figure 2, is a horizontal section on the line 2—2 of Figures 1 and 3;

Figure 3, is a vertical central section on the line 3—3 of Figure 2;

Figure 4, is a fragmentary vertical section on the line 4—4 of Figure 3;

Figure 5, is a perspective view of the 35 thermo element; and

Figure 6, is an electric circuit diagram.

In said drawings, 10 illustrates a receptacle body made of suitable insulation material, such as porcelain. The body comprises a base portion 11 and an upstanding central socket portion 12. The socket is hollow for receiving a screw shell 13 for receiving the usual form of incandescent electric lamp. The base 11 is provided with oppositely projecting securing lugs 14, and between these is provided on one side a connection lug 15, and on the opposite side with a connection lug 16.

The shell 13 is secured in position by two 50 screws 17 and 18 which pass down through suitable openings provided in the base. The screw 18 is secured by a nut 19 and the screw 17 is threaded into a suitable hole provided in the inner end of a flat metal 55 connecting member 20 which extends out through an opening in the base and over

the connection lug 15. The outer end of this member 20 carries a suitable binding screw 21 for clamping circuit wire 22. A central screw 23 is provided, the head of which 60 provides the central contact in the socket for the lamp. This screw extends through a central opening and it is held in place by a nut 24 on its lower end. The base is hollow to accommodate the connections. Above 65 the lug 16 and rising to the top of the central socket portion is a box-like portion 25, the walls of which are preferably formed integrally with the body 10. This box-like portion 25 is closed on two sides by vertical 70 walls 26 and is partly closed at its side opposite to the socket by a connecting wall 27. Within this pocket or box which extends down to the base 11 I arrange a thermo element 28. This element is a bimetallic strip 29 which stands up freely in the pocket 25 and has a bent off portion 30 at its lower end, the extreme end of which is clamped beneath the nut 24 which secures the central screw 23 in place. This strip is wound with an insulated wire 31 forming a heating coil, one end of this coil being soldered to the strip adjacent to its upper end at 32 and the opposite end being connected to a connection strip 32' which is arranged on the connection lug 16 and carries a clamping screw 33 for the other circuit wire 34.

The connection 32 is formed by bending outwardly the lower end of an upstanding strip 35 which extends up along side of and substantially parallel with the thermo element and carries at its upper end an adjustable contact screw 36. This screw is provided with a head 37 made of insulation material, so that the rate of flashing can be adjusted when the current is on without the danger of a shock. In order to prevent the screw 36 jarring or moving out of its adjusted position I turn the extreme upper end 38 of the strip 35 downwardly and spaced slightly from the body thereof, and I provide two registering openings, one in the body of the strip and one in the turned down end for the screw 36. Both these holes are threaded to loosely receive the screw, but due to the spring of the parts and the resiliency of the metal the threading is never accurately registered with the result that there is a binding effect upon the screw, sufficient to hold it from turning unless it is manually adjusted. Preferably

suitable non-corrosive contacts are provided at the point of contact of the inner end of the screw 36 and the thermo element 28.

In Figure 6 I have shown a diagram of the circuit when the winding of the thermo element is in shunt. In this instance the current enters at the binding post 21, passes to the shell 13, then to the lamp, back to the center screw, through the body 29 of the thermo element 28, then, the contacts of the adjustable screw 36 and the thermo element being separated, through the winding 31 of the thermo element to the base 32 of the member 35, thence out by means of the binding screw 33. As soon as the bi-metallic thermo element heats up it closes against the adjustable contact screw 36, thus permitting the current to by-pass the winding and flow directly through the member 35 to the binding screw 33. This decreases the current in the winding to practically nothing, and the thermo element cools off and swings away from the screw 36, thus opening the main circuit at this point.

While the thermo element is practically freely exposed to the air for rapid cooling, the surrounding walls amply protect it against inadvertent injury.

The receptacle is very simple compact and can be manufactured in quantities at a relatively low cost. Furthermore, the thermo element is relatively long, thus giving a wide range of adjustment, and the adjusting screw having a head which is insulated, the adjustment can be changed while the device is in circuit without danger to the operator.

As many modifications of my invention will readily suggest themselves to one skilled in the art, I do not limit or confine my invention to the specific details of construction and arrangement of parts herein shown and described except within the scope of the appended claims.

I claim:

1. In a device of the kind described, a unitary body member having an up-standing socket for an incandescent lamp base and a protected chamber of substantially equal height for housing a thermo element.

2. In a device of the kind described, a unitary body member having a socket por-

tion provided with attachment means, and an adjacent chamber rising alongside the socket portion for housing a thermo element.

3. In a device of the kind described, a unitary body member having a socket portion provided with attachment means, and an adjacent open topped chamber rising alongside the socket portion for housing a thermo element, and openings provided for freely admitting air for cooling purposes.

4. In a device of the kind described, a unitary body member having an open socket for receiving an incandescent lamp, or the like, and an integrally formed vertically elongated chamber rising alongside the socket for housing a thermo element.

5. In a device of the kind described, a body portion having an upstanding part arranged for connecting in an incandescent lamp, and integral walls forming a chamber alongside the upstanding part for receiving a thermo element, a thermo element secured at one end to the base of the device and extending up through said chamber, a make and break contact at the upper end thereof, and as and for the purpose specified.

6. In a device of the kind described, a unitary body member having a socket for receiving a cooperating electric current carrying member, and a chamber arranged at one side of the socket and extending longitudinally thereto for housing a thermo-electric control element.

7. In a device of the kind described, a socket for receiving a cooperating current carrying member, a thermo-electric control element arranged alongside the socket and extending in longitudinal parallel relation thereto.

8. In a device of the kind described, a base, an upstanding attachment socket thereon, and an upstanding chamber, the walls forming which are formed integrally with the wall of the socket, the chamber adapted to house a thermo-electric control element, and means carried by the base for cooperation therewith for intermittently supplying current to the socket.

In testimony whereof, I have hereunto set my hand, this 7th day of May, 1924.

JAMES W. PHELPS.
